To all whom it may concern:

Be it known that I, WILLIAM S. The lamp is of the contour shown in the drawing, comprising an annulus; a dome-shaped member above the annulus; a pair of arms depending from the annulus and curving inwardly and at their lower ends supporting a cup-shaped socket.

There is indicated in dotted lines in the drawing a support and lamp shade, which form no part of the design but are here represented for the purpose of showing the relation of the lamp to its accessories.
